UNITED STATES PATENT OFFICE.

JESSE B. ALLIGER, OF CHATTANOOGA, TENNESSEE.

SHIPPING-PACKAGE.

SPECIFICATION forming part of Letters Patent No. 541,820, dated July 2, 1895.

Application filed October 20, 1894. Serial No. 526,469. (No model.)

To all whom it may concern:

Be it known that I, JESSE B. ALLIGER, a citizen of the United States, residing at Chattanooga, in the county of Hamilton and State 5 of Tennessee, have invented certain new and useful Improvements in Shipping-Packages; and I do hereby declare the following to be a full, clear, and exact description of the invention, such as will enable others skilled in the 10 art to which it appertains to make and use the same.

This invention relates to an improvement in shipping cases or packages for containing goods of various kinds to be shipped from 15 point to point, such as flour, sugar, apples, potatoes, cabbages, or any article that is now being transported in what are called slack barrels, the packages being of a permanent character and hence capable of being used 20 over again for many things without impairment, and being also of a cheap and easily-built pattern so that they may be made at a minimum cost, and the invention relates more particularly to the special means for coupling 25 or locking together the sections of the package, and the invention therefore consists in the construction, arrangement and combination of parts, and in certain peculiarities and details thereof, substantially as will herein- 30 after be fully described and claimed.

In the annexed drawings illustrating my invention, Figure 1 is an elevational view of my improved shipping package complete, with the sections fastened together. Fig. 2 is a side 35 elevation of a series of empty sections nested together in a compact form for easy shipment. Fig. 3 is a top perspective view of one of the sections or halves of the barrel. Fig. 4 is a sectional view on the line 6—6 of Fig. 1. Fig. 40 5 is a sectional view on the line 5—5 of Fig. 1. Fig. 6 is a plan and an end view of one of the locking wedges. Fig. 7 is a perspective view of one of the wedges.

Like letters of reference denote like parts 45 in all the different figures of the drawings.

My improved shipping package is preferably made in the form of a barrel or cask, although I do not wish to be restricted to this shape, and can make it in any other desired 50 shape, and consists of two half-barrels or sections A A' of similar form, which are adapted

to be attached together to constitute the complete package, or to be detached from each other to permit the removal of the contents of the package.

The periphery of the section A is provided with a circular tongue a^3 , which fits tightly into a receiving groove a' , provided therefor in the corresponding periphery of the other section A'. This tongue and groove however 60 may be dispensed with, as I do not deem them essential, although they are a convenience. The contacting edges of these sections A A' are further provided with dovetailed notches or recesses a , those on the edge of one section 65 being in coincidence with those on the edge of the other section, as shown in Fig. 1, so that a series of double-dovetailed mortises, extending into both edges of the sections, are thereby provided.

B B denote peculiarly-shaped locking wedges of doubly-dovetailed form, and of proper size to fit into the dovetailed mortises $a a$. By means of these wedges the sections A and A' are firmly locked together. Each 75 wedge B has the two dovetailed reversely-situated tenons C C. The under face of the wedge is preferably straight and flat, but the other and outer face is reversely-inclined, that is to say, the faces of the two tenons C C are inclined in opposite directions from a transverse or cross line c, which divides them, said inclinations corresponding to the inclinations of the walls of the barrel sections A A', so that when the wedges are in position in the 85 mortises as shown in Fig. 5, their outer faces will be flush with the external surface of the barrel. Also it will be observed that the longitudinal edges of the wedges B, are splayed, sloped, or inclined at C' so as to enable them 90 to fit the better into the mortises a , whose edges are correspondingly inclined at a^3 . These inclinations a^3 , provide seats as it were, in mortises a , so that when the wedges B are introduced into the mortises from without 95 they will rest tightly and closely therein with the faces of the tenons C flush with the barrel as stated.

In order to keep the wedges B in place after they have thus been situated in the mortises, 100 and thereby enable them to effectually bind the two sections A A' together, I employ hoops

D D which are driven over the barrel in the ordinary way until they surround the series of wedges B and firmly keep them in their places.

5 By constructing a shipping package in this manner many advantages can be secured. In transporting the empty packages the sections may be nested as shown in Fig. 2, and thus caused to occupy much less space than would be necessary for packages of the usual form. Thus freight charges will be diminished and a great saving effected. They are also handled much easier than the full-sized packages or barrels. Also there is the advantage of using the barrels over and over again without appreciable deterioration or impairment. When the sections are combined, a tight joint is made and the sections will be inseparable so long as the hoops are kept in place and the joint maintained.

In shipping produce such as apples, pears, onions, cabbage, potatoes, &c., by raising the hoop D and removing the wedges the package can be used as two display packages.

25 Having thus described my invention, what

I claim as new, and desire to secure by Letters Patent, is—

1. A shipping package consisting of sections having dovetail mortises in the edges, wedges engaging these mortises having splayed edges, 30 and shaped on the outer face to correspond with the inclination of the barrel sides, and a retaining device for the wedges.

2. A shipping package consisting of sections having dovetail mortises, wedges engaging 35 them having doubly-inclined outer faces and splayed edges, and engaging the mortises, substantially as described.

3. The combination of the sections having dovetail recesses whose edges are inclined, 40 the double dovetail wedges having doubly-inclined outer faces and splayed edges, and seated in the recesses, and a retaining hoop, substantially as described.

In testimony whereof I affix my signature 45 in presence of two witnesses.

JESSE B. ALLIGER.
